CLAIM

The ornamental design for a woven circular tea table, as shown and described.

DESCRIPTION

FIG. 1 is a front view of a woven circular tea table showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines depict portions of the woven circular tea table that form no part of the claimed design.
